(57) **CLAIM**

The ornamental design for a canning funnel as shown and described.

DESCRIPTION

FIG. 1 is a front view of the canning funnel showing my new design;

FIG. 2 is a rear view of the canning funnel depicted in FIG. 1;

FIG. 3 is a left, side view of the canning funnel depicted in FIG. 1;

FIG. 4 is a right, side view of canning funnel depicted the in FIG. 1;

FIG. 5 is a top view of the canning funnel depicted in FIG. 1;

FIG. 6 is a bottom view of the canning funnel depicted in FIG. 1;

FIG. 7 is a top, right perspective view of the canning funnel depicted in FIG. 1; and,

FIG. 8 is a bottom, right perspective view of the canning funnel depicted in FIG. 1.

The broken lines in the drawings illustrate portions of the canning funnel that form no part of the claimed design.

1 Claim, 8 Drawing Sheets
